[57] CLAIM

The ornamental design for a line detector camera for a dental x-ray diagnostics apparatus, as shown and described.

DESCRIPTION

FIG. 1 is a front elevational view of the line detector camera of the present invention removed from a dental X-ray diagnostics apparatus;

FIG. 2 is a side elevational view of the left side of the line detector camera of FIG. 1;

FIG. 3 is a top plan view of the line detector camera of FIG. 1;

FIG. 4 is a back elevational view of the line detector camera of FIG. 1;

FIG. 5 is a side elevational view of the right side of the line detector camera of FIG. 1; and,

FIG. 6 is a bottom plan view of the line detector camera of FIG. 1.
